UNITED STATES PATENT OFFICE.

RICHARD T. TODHUNTER, HARRY A. DUKE, AND ALEXANDER WOODS, OF BARNES-BORO, PENNSYLVANIA.

TROLLEY-HANGER.

1,342,034.

Specification of Letters Patent.

Patented June 1, 1920.

Application filed March 6, 1919. Serial No. 281,013.

To all whom it may concern:

Be it known that we, RICHARD T. TODHUNTER, HARRY A. DUKE, citizens of the United States, and ALEXANDER Woods, subject of the King of Sweden, residing at Barnesboro, in the county of Cambria and State of Pennsylvania, have invented certain new and useful Improvements in Trolley-Hangers, of which the following is a specification, reference being had therein to the accompanying drawings.

This invention relates to a trolley hanger, and has for its object the construction of a trolley hanger that is comparatively simple, yet efficient in operation and durable in construction.

With this and other objects in view our invention comprises certain novel combinations and arrangements of parts as will be hereinafter specifically described, illustrated in the accompanying drawing, and more particularly pointed out in the appended claim.

In the drawings:

Figure 1 is a view in side elevation of a trolley hanger constructed in accordance with the present invention, while

Fig. 2 is an end view of the hanger, showing the jaws in their outward extended position, and the trolley wire displaced from between the jaws.

Fig. 3 is a sectional view taken on line 3—3 Fig. 1.

Fig. 4 is a top plan view of the hanger shown in Fig. 1.

Fig. 5 is a view in side elevation, looking at the interior of the auxiliary jaw, while

Fig. 6 is a similar view of the primary jaw.

Referring to the drawings by numerals, 1 designates the primary jaw, and 2 the auxiliary jaw. The primary jaw comprises a body having a longitudinal extending groove 3, an inwardly extending bead or rib

4, and an outwardly curved or beveled portion 5. Integral with the grooved portion 3 is an auxiliary grooved portion 3^a (Fig. 6), and integral with this grooved portion 3^a are alined, integral sleeves 6, 6.

A vertically extending sleeve portion 7 is similar in construction to the sleeve portion 7 on auxiliary jaw 2 (Fig. 5). A stub pin 8 extends beyond the inner face of the rib 4 (Fig. 3) for the purpose hereinafter specified.

On the auxiliary jaw 2, and in alinement, are a pair of auxiliary sleeves 6^a, that, when the two jaws are placed together, as shown in Fig. 3, register in alinement, so that a shaft or nail 9 can be run through 60 these sleeves, as well as the anchor bolt 10, holding all of the parts of our hanger in an assembled position.

The anchor bolt 10 is externally threaded, and is adapted to be threaded into the conical portion 11 of the member which may be attached to a suitable support 12. The conical portion 11 fits into the conical sockets 11^a of the sleeve portions 7 of the jaws and by rotating the attaching member 12 with 70 respect to the anchor bolt 10, the jaws 1 and 2 can be closed more tightly upon their pivot, constituted by the fastening member 9, or can be loosened, as desired, to control 75 the pressure exerted upon the trolley-wire 13.

The trolley-wire 13 is placed between the removable metal trolley engaging plates 14, 14, which plates fit the portions 3 and 5 of the jaws; these plates are provided with channels 15 that permit one or more trolley-wires 13 to be supported upon our hanger, or if one edge of the plates become worn, the plates can be reversed in the hanger, exposing a non-worn edge, if desired. The pins 8 project at their inner ends into apertures 16 formed in the plates 14; these apertures 16 being formed between the channels 15, Fig. 3. These pins 8 provide temporary means for holding the plates 14 between the jaws until the trolley-attaching member 12 80 is screwed upon the anchor bolt 10 sufficiently to cause the jaws 1 and 2 to tightly clamp the trolley-wire 13 through the medium of the plates 14. By unscrewing the attaching member 12, moving the same outward or upward upon the anchor bolt 10 85 (Fig. 2) the jaws may be thrown apart and the trolley-wires 13 permitted to be dropped out of the jaws as shown.

The alined sleeves 6 fit against the outer 100 ends of the sleeves 6^a on the auxiliary jaw, whereas the sleeves 6^a fit against the inner ends of the sleeves 6 on the primary jaw when the parts are in their assembled position, then the anchor bolt is placed down 105 in between the jaws until the apertures formed therein near its lower end register with the apertures or interior of the sleeves 6 and 6^a, then the fastening member 9 is run through the sleeves and the anchor bolt, 110

whereupon the interiorly-threaded attaching member 12 can be screwed upon the anchor bolt, closing the lower ends of the jaws together upon the trolley-plates 14 and the trolley-wire 13. It will be noted that the action of the trolley attaching member threaded upon the anchor bolt 10 is that of a wedge for wedging the jaws together at their trolley-wire supporting ends.

10 The trolley hanger herein described can be attached to a support (not shown) in any suitable manner.

What we claim is:

15 In a device of the class described, the combination, of a pair of elongated jaws, each jaw provided with a pair of alined sleeves and with a longitudinally extending groove and with a beveled lower portion, each jaw being provided with a longitudinally extending rib between the groove and the beveled lower portion, each jaw being provided with a pin extending inwardly upon said rib, a pair of channel trolley-sup-

porting plates upon said pins and resting in said grooves and beveled portions, each jaw 25 being provided with a vertical sleeve portion, said vertical sleeve portion provided with conical faces, an externally-threaded anchor bolt provided with an aperture near its lower end positioned between said jaws 30 and between said sleeves of the jaws and having its aperture registering with the apertures of the alined sleeves, a detachable fastening member extending through the aperture of the alined sleeves and the aperture of the anchor bolt, and an attaching member threaded upon said anchor bolt and having a conical portion positioned in the vertical sleeve portions of the jaws and bearing against the conical faces thereof, 40 substantially as shown and described.

20 In testimony whereof we hereunto affix our signatures.

RICHARD T. TODHUNTER.

HARRY A. DUKE.

ALEXANDER WOODS.
